[57] CLAIM

The ornamental design for a tether ball game base, as shown and described.

DESCRIPTION

FIG. 1 is a perspective view of the tether ball game base according to my design;

FIG. 2 is a top view of FIG. 1;

FIG. 3 is a bottom view of FIG. 1;

FIG. 4 is a side elevational view of FIG. 1;

FIG. 5 is an end elevational view of FIG. 1; and

FIG. 6 is a second elevational end view of the present invention.

FIG. 1

FIG. 2

FIG. 3

FIG. 4

FIG. 5

FIG. 6
